STRAND OF BEADS FOR CURTAIN ELEMENTS
OR THE LIKE

Irving Levine, 23555 Park Belmonte,
Calabasas Park, Calif. 91302

Filed July 5, 1974, Ser. No. 486,094

Term of patent 14 years

Int. Cl. D6—10

U.S. Cl. D6—205

Fig. 1

Fig. 2

Fig. 3

FIG. 1 is a side elevation view of a strand of beads for curtain elements or the like showing my new design, the bead units repeating, in the sequence shown, to an indeterminate length;

FIG. 2 is a top plan view thereof taken in the direction of the line 2—2 of FIG. 1; and

FIG. 3 is a bottom plan view taken in the direction of the line 3—3 of FIG. 1.

I claim:

The ornamental design for a strand of beads for curtain elements or the like, substantially as shown.
